UNITED STATES PATENT OFFICE.

VINCENT V. VEENSCHOTEN, OF ERIE, PENNSYLVANIA.

FEED-WATER REGULATOR.

1,399,281.

Specification of Letters Patent.

Patented Dec. 6, 1921.

Application filed December 16, 1918. Serial No. 266,270.

To all whom it may concern:

Be it known that I, VINCENT V. VEENSCHOTEN, a citizen of the United States, residing at Erie, in the county of Erie and 5 State of Pennsylvania, have invented certain new and useful Improvements in Feed-Water Regulators, of which the following is a specification.

This invention relates to feed-water regulators, and particularly to regulators which 10 are adapted to generate steam, the pressure of which depends upon the elevation of the water in the boiler, and to operate by this steam the feed-water valve. Such a generator is illustrated and described in the Patent 15 #1193125 issued to N. G. Copley, August 1st, 1916. And one object of the invention is to provide improved means for supplying water to the generator of the regulator.

20 Of the accompanying drawings Figure 1 is an elevation, more or less diagrammatic, of a boiler, and a boiler feed-water regulator connected therewith which embodies features of my invention. Fig. 2 is a central 25 sectional view of the regulator and the feed-water valve; and Fig. 3 is a modified form of the regulator.

The regulator 19 comprises a tube 27, which is connected, by means of pipes 28 and 30, above and below the water-level in the 30 boiler 30. The tube 27 therefore has more or less steam in its upper end and water in its lower end, depending upon the elevation of the water-level in the boiler. Inclosing 35 this tube 27 is tube 31 partly filled with water 32; and the tube 33, the tank 34 and the tube 35 connects the tube 31 with the diaphragm controller 36.

In operation, as the water in the boiler 40 sinks steam will be generated in the tube 31 of the regulator, due to the increasing amount of steam in the tube 27; and the pressure of the steam generated will depend much upon the elevation of the water in the 45 tube 27. Thus the pressure of the steam generated, and hence the fluid pressure in the diaphragm chamber 38, will depend more or less on the elevation of the water in the boiler; and this pressure in turn, by 50 means of the diaphragm and the members connecting it with the plunger 37, will determine the position of the plunger; and hence will determine the amount of flow of water to the boiler through the feed-water 55 valve 39.

In use it has been found that the amount of water in the regulator tube 31 continually decreases, and has to be replaced periodically; so that the water-level in the tube may vary greatly, and hence is often a very 60 material distance below the water-level in the tube 27, when the latter level is high, although in practice it should be above the latter level. These irregularities materially affect the steam pressure generated in the 65 tube 31 under similar conditions; because, while, with high level in the tube 31, there might be ample steam pressure generated therein, yet with low water level in the tube 31 the steam pressure therein would increase 70 but very slightly as the water level in the boiler sank, and might not, in some cases, be sufficient to move the plunger before injury to the boiler resulted. This tendency is much increased, ordinarily, by connecting 75 the tube 33 to the lower end of the generator, as shown in the said Patent #1193125. When thus arranged as the water-level in the boiler sinks the water in the tube 31 is forced down into the diaphragm chamber, and 80 hence the water level in the tube sinks materially lower; and this has a tendency to neutralize the effect on the steam pressure generated of the decreased level of the water in the tube 27. In fact the only increased 85 pressure effect, if any, is due to a slight heating of the steam; as no additional steam otherwise can be generated when the water-level in the tube 27 is above that in the tube 31. 90

To maintain more nearly uniform the elevation of the water in the tube 31 I have connected the pipe 33 to the tube 31 at substantially the desired water-level elevation in the tube; and have also connected the 95 tube 33 with the reservoir 34. This reservoir has a very material horizontal cross section compared with the cross section of the generator tube 31, and, hence, by the insertion of the reservoir in the manner 100 shown, the water-level in the tube 31 will be maintained at substantially the same elevation as the water-level in the reservoir, because, as the water in tube 31 passes off by leakage or steam or otherwise, water 105 will flow from the reservoir into the tube; and in addition it is impossible for the water in the tube 31 to be forced below the entrance to the tube of the pipe 33. As a consequence the water-level in this 110

tube, whether or not the controller is being operated, remains at all times substantially uniform.

In order to supply water to the reservoir 5 34 any suitable means may be provided. I prefer for this purpose a pipe 40 connected with any suitable source of water supply under pressure, passing downwardly from the reservoir to a point where it can 10 be conveniently reached by the operator in charge. I provide, also, a similar pipe 41 leading to the same point, and which is adapted to release the pressure in the reservoir so as to allow the water to flow 15 into the reservoir when both valves 42 and 43 are opened. The pipe 41 opens into a sink, or other suitable receptacle; and the water will flow therefrom as soon as the reservoir is sufficiently filled; and this will 20 indicate to the operator the fact that sufficient water has been supplied.

Fig. 3 shows a modified form of a reservoir and its connection to the generator. In this instance the reservoir 44 is elevated 25 above the generator, and the pipe 45 passes from the reservoir into the tube 46, and downwardly to substantially the position of the desired water-level in the tube. This reservoir may be supplied with water by 30 means of the water pipe 47 and a four way valve 48 operated by means of a chain 49 which passes downwardly so as to be conveniently reached by the operator. The valve 48 for clearness is shown open, but 35 in normal operation the valve would be closed. With this arrangement the water level in the tube 46 will be maintained somewhat uniform, but will depend more or less upon the pressure of the steam therein. 40 When the steam is sufficient to operate the diaphragm the water level will be forced downwardly by the steam until it is slightly below the end of the tube 45, but will, under no circumstances pass below this point. 45 By this arrangement a minimum water-level is provided for; and the maximum water level will occur when the water level in the boiler is at a maximum and hence the

steam effect in the tube 50 is at a minimum. In general the level of the water in the tube 50 46 will follow more or less the movement of the water level in the boiler, and will thus adapt itself to the needs.

I claim as my invention:

1. The combination of a boiler and a feed-water regulator, said regulator comprising a vessel adapted to contain water and mounted at an angle to the horizontal adjacent said boiler and at substantially the same elevation as the mean water-level in 60 said boiler, a tube passing through said vessel and connected with said boiler above and below the mean water-level therein, a feed-water valve operatively connected with said boiler, a governor operatively connected with said valve and adapted to be operated by steam pressure, a reservoir mounted at substantially the same elevation as the mean water level in said boiler, a pipe operatively connecting the lower portion of said 70 reservoir with said governor, a pipe connecting said reservoir with said vessel, means for admitting water into said reservoir, and means for relieving the pressure in the upper portion of said reservoir. 75

2. The combination of a boiler and a feed-water regulator, said regulator comprising a vessel adapted to contain water and mounted at an angle to the horizontal adjacent said boiler and at substantially 80 the same elevation as the mean water-level in said boiler, a tube passing through said vessel and connected with said boiler above and below the mean water-level therein, a feed water valve operatively connected with 85 said boiler, a governor operatively connected with said valve and adapted to be operated by steam pressure, a reservoir mounted at substantially the same elevation as the mean water level in said boiler, a pipe operatively connecting the lower portion of said reservoir with said governor, and a pipe connecting said reservoir with said vessel. 90

In testimony whereof, I hereunto set my hand.

VINCENT V. VEENSCHOTEN.
